KEY RING

Harold B. Oldak, East Rockaway, N. Y.

Application June 14, 1955, Serial No. 36,504

Term of patent 14 years

(Cl. D17—14)

Fig. 1.

Fig. 2.

Fig. 3.

Fig. 4.

Fig. 1 is a front elevational view of a key ring showing my new design;

Fig. 2 is a right side elevational view thereof;

Fig. 3 is a top plan view thereof;

Fig. 4 is a left side elevational view thereof, and

Fig. 5 is a front elevational view similar to Fig. 1 with the ring in open position.

I claim:

The ornamental design for a key ring, as shown.
